DISPENSING CLOSURE

Robert E. Hazard, North Kingstown, R.I., assignor to
Polytop Corporation, Slatersville, R.I.

Filed Aug. 2, 1971, Ser. No. 168,533

Term of patent 14 years

Int. Cl. D9—07

U.S. Cl. D9—275

FIG. 1.

FIG. 7.

FIG. 8.

FIG. 2.

FIG. 3.

FIG. 4.

FIG. 5.

FIG. 6.

FIG. 1 is an isometric view of a dispensing closure embodying my new design;

FIG. 2 is a front elevational view;

FIG. 3 is a rear elevational view;

FIG. 4 is a side elevational view, the opposite side being a mirror image of the side shown;

FIG. 5 is a top plan view;

FIG. 6 is a bottom plan view;

FIG. 7 is an isometric view showing the closure in an open configuration; and

FIG. 8 is a view similar to FIG. 1 but showing a modified form of my new design.

I claim:

The ornamental design for a dispensing closure, substantially as shown and described.
